CLAIM

The ornamental design for a tool box as shown and described.

DESCRIPTION

FIG. 1 is a top perspective view of a tool box showing my new design;

FIG. 2 is a bottom perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof; and,

FIG. 9 is a top perspective view in an open configuration thereof.

The broken lines in the drawings depict portions of the tool box that form no part of the claimed design.
